UNITED STATES PATENT OFFICE

ROY F. GOULD, OF CHICAGO, ILLINOIS, ASSIGNOR, BY MESNE ASSIGNMENTS, TO
ASSOCIATED ELECTRIC LABORATORIES, INC., OF CHICAGO, ILLINOIS, A CORPORA-
TION OF DELAWARE

SIGNALING SYSTEM

Application filed November 8, 1929. Serial No. 405,780.

This invention relates to signaling systems in general, but, more particularly, to such systems wherein the signals are transmitted from one or more sending stations 5 to remotely disposed receiving stations, the signals comprising series of impulses corresponding to digits of numbers.

The system of my invention, to be disclosed in detail subsequently, is particularly 10 adaptable for use in newspaper printing plants to convey information to the various branches of the plant concerning the status of the making of the matrices, so that the printing of the newspapers may be completed in the shortest period of time possible 15 and with the least number of delays.

Briefly, as news is set into type by the linotype machines, the forms for the sheets 20 of an edition of the newspaper are made up from the lines of type from the machines. When a form is completed, it is sent to the foundry and a mold is made thereof. From the mold, the matrices are cast and as completed, 25 are sent to the electrotyping room where they are finished and bent into shape to fit the cylindrical presses. Each matrix is inspected when finished and either passed or rejected. If rejected, the matrix is returned to the foundry and either repaired 30 or scrapped, a new one being made in case the other is scrapped. If passed, the matrix will be sent to the pressroom.

In the pressroom, the printing presses are 35 scheduled to run certain sheets of an edition. Therefore, it can be seen that it is of vital importance to the pressroom to know when a certain matrix has passed inspection, because the pressroom will know from that 40 how long it will be before the matrix is received in the pressroom.

The information concerning inspection is also of importance to the linotype room, to the foundry, and to the electrotyping room. It is, therefore, the duty of the 45 inspector to notify these rooms as he finds a matrix to be satisfactorily constructed.

Accordingly, I have assumed as the principal object of my invention, the provision of a system which will allow the inspector 50 to simultaneously notify the various rooms

in a reliable, speedy, and accurate manner, that a matrix has passed inspection.

In actual practice, there are so many matrices passing through inspection that it would be impractical for the inspector to 55 stop after each inspection and notify the various rooms since, in the newspaper printing business, a matter of a small period of time is of great importance. Therefore, a 60 signaling operator is usually employed for the purpose of transmitting the information, and, in the case of large newspaper plants, more than one operator is often necessary. Therefore, I have shown the 65 system of my invention as employing two operators.

The various features and other objects not specifically mentioned herein, will be 70 apparent from the detailed description to follow when studied in conjunction with the accompanying single sheet of drawing, which, by means of the usual symbols, presents the system of my invention in dia- 75 grammatic form, only such equipment being shown as will enable the reader to obtain a complete understanding of the operation and adaption of the system.

The two operator's positions, or transmitting stations, are shown at the left-hand side of the sheet of drawing, to the left of the dotted vertical line, and are designated on the drawing by transmitting station No. 1 and transmitting station No. 2. Each of these stations is provided with a plurality 80 of keys and signal lamps whose functions will be pointed out subsequently. In addition to these, each transmitting station is provided with an impulsing device S having the shunt springs 1 and 2 and the impulse springs 3 and 4. The impulsing device S is of the finger dial type familiar to 85 those skilled in the art. It is thought necessary to only point out that the shunt springs 1 and 2 of the device are operated when the finger dial is turned from its normal position and remain in engagement until the finger dial has returned to its normal position, and that the impulse springs 3 and 4 90 are only operated with the return-to-normal movement of the finger dial. 100

Associated with each of the transmitting stations is a selector E which is of the two directional motion type, having wipers which move in a vertical direction and 5 thence in a rotary direction. A selector switch of this character is shown and described in Reissue Patent No. 14,411, issued to R. H. Burfeind on December 18, 1917. Since the selector E' associated with transmitting station No. 2 is identical with the selector E associated with station No. 1, only the relay 5' and the springs controlled thereby have been shown since the operation of the selector E' will be readily understood from a description of the operation of the selector E.

Selector E has two wipers, 31 and 32. The wiper 31 is elevated by the action of the vertical magnet of the selector and is 20 then rotated by the action of the rotary magnet. The bank of contacts accessible to the wiper 31 is arranged in ten horizontal rows of ten contacts each, in the well known manner. The wiper 32 is elevated by the 25 action of the vertical magnet and is also rotated under the action of the rotary magnet. Wiper 32 has access to only ten contacts which are arranged in a single, vertical row. The rotary movement of wiper 32 30 disengages the wiper from whatever contact it is in engagement with as the result of the vertical movement.

The selector E' is provided with two banks of contacts identical with those to which 35 wipers 31 and 32 of selector E have access. Corresponding contacts in the banks of selector E' are multiplied to corresponding contacts of the banks of selector E.

In the upper right-hand corner of the 40 drawing is a dotted rectangle which represents one of the register panels. This panel is provided with one hundred and ten signal lamps, one hundred of which are associated with the bank to which wiper 31 has access, 45 while the other ten are associated with the bank to which wiper 32 has access. The circuit of each lamp 40 is controlled by a relay similar to relay 34. Therefore, there will be one hundred and ten such relays. 50 Each of the ten relays associated with the ten lamps which, as said before, are associated with the contacts accessible to wiper 32, has its winding connected to one of the contacts accessible to wiper 32 of each of the 55 selectors. Thus, each of the ten relays may be operated from either of the selectors.

Each of the other one hundred relays has its winding connected to one of the contacts of the banks accessible to wiper 31 of each 60 of the selectors, and may be operated through either of the selectors.

Since, as previously stated, it is important that each of the various rooms be notified when a matrix has passed inspection, each of 65 those rooms will be furnished with a register

panel similar to that just described. In order that a signal may be registered upon all panels simultaneously, the windings of all corresponding relays will be connected in parallel to the bank contacts as indicated 70 by the arrows on conductor 43.

The arrangement of each register panel is such that when one of the signal lamps is lighted, it will cause to be exposed on the face of the panel any symbol which may 75 be required by the particular use to which the system is employed. Lamp panels of this character are well known and need no further explanation. In the present system, anyone of the lamps associated with 80 the banks accessible to wiper 31 will expose numerals to indicate the page number of the edition of the newspaper, and any one of the ten lamps associated with the banks accessible to wiper 32 will cause the 85 exhibition of letters corresponding to the various names of the editions.

In describing the operation of the system, it will be assumed that operations for the day at the printing plant are about to begin. In this case, the matrices for the first edition of the paper will be in the process of manufacture. The operator at transmitting station No. 1 will, as his first operation, display on the register panels the name of 90 the edition about to go to press. In order to do this, he will first operate his start key SK and then operate his impulsing device S to operate the selector E to raise the wiper 32 to the contact associated with the 95 lamp of the register panel which will exhibit the name of the edition. Having done this, he will then release the start key SK, which release causes the release of selector E. As selector E releases, it completes the 100 circuit of the relay connected to the contact upon which wiper 32 is resting. The operation of the relay, such as relay 34, lights the lamp to exhibit the name of the edition.

As each matrix is passed by the inspector, the operator will operate the start key and impulsing device to operate the selector E. However, in these cases, the operations of the impulsing device S will be for two digits and the selector will, therefore, first elevate its wipers and then rotate them in accordance with the series of impulses transmitted. The release of selector E after each complete transmission, causes the operation of the relay associated with the 110 contacts into engagement with which the wiper 31 has been placed. Since the relay is not operated until the switch is released, the operation of wiper 32, in accordance with the first digit of the number of the 115 matrix, has no effect since it is rotated out of engagement with its bank contacts by the operation of the selector in accordance with the second digit of the number of the matrix. 120 125 130

The matrices for pages 10 to 99, inclusive, of the edition, bear the number corresponding to the number of the page. In order to avoid operation of relays through wiper 32 when transmitting the numbers of matrices, the matrices for pages 1 to 9, inclusive, of the edition are numbered 01 to 09, inclusive, respectively.

Should a matrix become so damaged after it has passed inspection that it has been found necessary to make a new one or to have it repaired, the operator at the transmitting station will indicate this by causing the registration on the panel, corresponding to that matrix, to be wiped out. This operation will be described in detail subsequently. When all matrices for an edition have passed inspection and have been received by the pressroom, the operator may by the operation of his key CWK, wipe out all registrations on all of the panels. This operation also will be described subsequently.

Should the selector E get out of operating order, the operator at transmitting station No. 1 can, by the operation of the change-over key COK, use the selector E' associated with transmitting station No. 2, provided that at that time the selector E is not in use.

A general description of the operation of the system, having been given, a detailed description thereof will now be given.

Assume that the signal lamp 40 in the register panel shown is the lamp which the operator wishes to light to exhibit on the panel the name of the edition about to go to print. It will be noted that the winding of relay 34 is connected to the first contact in the bank of wiper 32. Therefore, in order to select lamp 40, the selector E must be operated to raise its wiper 32 one step. To do this, the operator will depress the start key SK and hold this key depressed while he is manipulating the impulsing device. The operation of key SK completes the circuit for relay 10 in series with the lower winding of relay 16 by way of resistance element R and armature 6 and resting contact of relay 5. Resistance element R is of such value that relay 16 will not secure enough current through that resistance to energize sufficiently to attract its armature. Relay 10 energizes, however, and attracts its armatures. At armature 11 of relay 10, the circuit of relay 8 is completed from ground by way of the spring contacts of the start key, impulse springs 3 and 4, armature 7 of relay 5 and its resting contacts, and armature 11 and its make contact. At armature 12 of relay 10, the impulsing circuit of the selector is prepared. At armature 13 the obvious circuit of relay 26 is completed. At armature 14 of relay 10 a point in the circuit of wipers 31 and 32 is opened. Relay 8 energizes when its circuit is com-

pleted, and opens the impulsing circuit at armature 9.

Relay 26 energizes when its circuit is completed and attracts its armatures 27 to 30, inclusive, at armature 27, closing a point in the circuit of the wipers 31 and 32 at armature 28 removing ground from the release magnet circuit, at armature 29 preparing the impulsing circuit, and at armature 30 completing the circuit of the lamp 41' at the transmitting station No. 2 to indicate to that station that the selector E is in use.

In order to operate the selector E to raise the wipers one step, the operator inserts his finger in the No. 1 hole of the finger dial and turns the dial from its normal position. As the dial is turned off-normal, shunt springs 1 and 2 engage to connect ground to the impulsing circuit, which ground will be independent of that furnished by key SK. When the finger dial is released and allowed to return to normal, the impulse cam causes a momentary separation of impulse springs 3 and 4, thereby momentarily opening the circuit of relay 8. The momentary opening of the circuit of relay 8 causes the armature 9 thereof to momentarily complete the impulsing circuit, this circuit being completed from ground by way of armature 29 of relay 26, resting contact in armature 9, armature 12 and its make contact, off-normal springs 21 and 19, winding of series relay 22, winding of vertical magnet 24 to battery. Vertical magnet 24 momentarily operates and, in so doing, elevates the wipers 31 and 32 one step, placing wiper 31 opposite the first horizontal row of contacts and placing wiper 32 in engagement with the first contact of its bank. The elevation of the wipers causes the operation of the vertical off-normal springs. When this occurs, springs 21 and 19 will disengage and springs 20 and 21 will engage each other, while springs 37 and 38 in the release magnet circuit engage each other.

If the circuit of relay 8 had been opened a number of times momentarily, a plurality of impulses would have been transmitted to the vertical magnet. Relay 22 being a slow to release relay because of the copper slug on the heel end of its core, after energizing in series with the vertical magnet 24 on the first impulse, remains in its energized position throughout the plurality of impulses, and returns to its deenergized position shortly after the termination of the last impulse of the series. After the first vertical step of the wipers, that is after the impulse springs 20 and 21 have come into engagement with each other, the impulse circuit now will include springs 21 and 20 and armature 23 and its make contact.

After the operation of the calling device by the operator, the start key SK is released and consequently the circuits of relay 10 and

- relay 8 will be open. Relay 10 upon releasing retracts its armature 14 to complete a circuit for relay 34 at the register panel from battery by way of release magnet 15, off-normal springs 37 and 38, resting contact and armature 17 of relay 16, armature 14 and resting contact of relay 10, armature 27 and make contact of relay 26, wiper 32, the first contact in the bank of wiper 32, conductor 43 to ground through the winding of relay 34. It should be noted here that, although at its armature 18 relay 10 opens the circuit of relay 26, relay 26 because of the copper slug on the heel end of its core, maintains its armatures in the attracted position for a short interval after its circuit is opened. This interval is long enough, however, to allow the relay 34 to energize. Relay 34 upon energizing, at its armature 36 completes a locking circuit for itself through the non-inductive resistance NI to conductor 44 and at its armature 35 completes the circuit for the signal lamp 40 to exhibit the name of the edition on the panel.
- 26 When relay 26 deenergizes, it retracts its armatures, thereby at armature 28 completing a circuit for the release magnet 15. Although the circuit for the release magnet 15 is completed in series with the relay 34, release magnet 15 is marginal and does not receive sufficient current in series therewith to cause it to operate. When the release magnet circuit is completed by way of armature 28 and its resting contact, the selector E will release and the wipers 31 and 32 will be returned to their normal positions. This return to the normal position of the wipers opens the off-normal springs 37 and 38 and closes the off-normal springs 19 and 21. The impulsing circuit is also opened by the release of relay 26. The circuit for the lamp 41' at the transmitting station No. 2 is also opened by the release of relay 26 to indicate that the selector E is no longer in use.
- 45 Since the relay 34 at the register panel is locked in its energized position, the circuit for the signal lamp 40 will be maintained completed until some operation is performed to release the relay 34.
- 50 When a matrix passes inspection, the inspector notifies the operator of the number of that matrix, in other words, the number of the page of the newspaper, and the operator then operates his impulsing device in accordance with the digits of that number, operating first his start key SK and holding the key SK depressed throughout the operation of the impulsing device.
- In accordance with the number of impulses comprising the first digit of the number of the matrix, the selector E raises its wipers 31 and 32 a corresponding number of steps. After the last impulse of the first series has been received by the vertical magnet 24, the series relay 22 deenergizes and

by the retraction of its armature 23 prepares the circuit of the rotary magnet 25.

In accordance with the number of impulses in the series corresponding to the second digit of the number of the matrix, the rotary magnet rotates the wipers 31 and 32 a number of steps corresponding thereto. The rotation of wiper 31 moves it into engagement with the contact of its bank corresponding to the number of the matrix. The rotation of wiper 32 moves it out of engagement with the contact of its bank.

When the selector is released as before, battery through the release magnet 15 is again connected by way of armatures 14 and 27 to the wipers 31 and 32. Since wiper 32 is not in engagement with any contact of its bank, connection of battery to it has no effect.

The connection of the battery to wiper 31 completes the circuit of the relay, similar to relay 34, whose winding is connected to the bank contact which the wiper 31 engages. That relay energizes and locks itself as would relay 34 and completes the circuit of the signal lamp associated therewith, thereby exhibiting on the panel the number of the matrix which has just passed inspection. Since there are three other panels similar to that shown, the connection of battery to wiper 31 operates the other three relays as was just described for the one relay. Thus the numeral, or matrix number, is simultaneously displayed upon the four different panels. The return of the selector E to its normal position is completed as explained when the relay 26 deenergizes to complete an independent circuit for the release magnet 15.

Inasmuch as it is unlikely that the two operators at stations No. 1 and No. 2 will ever desire to transmit the same number, it is possible for both operators to set up numbers on the same panels at the same time.

Since there are one hundred relays in each panel connected to the bank of wiper 31, and since there are ten relays in each panel connected to the bank wiper 32, there can be one hundred and ten signals displayed upon each panel at one time. Since it is unusual for a newspaper to have one hundred and ten pages, it is unlikely that all of the signals on the lamp panel will be lighted at one time.

In the case where a matrix becomes damaged and the operator desires to wipe out the number of that matrix if it is on the panel, he can do so by operating the single number-wipe-out key IWK and operate the impulse device S in accordance with the number of that matrix. By operating the single number-wipe-out key IWK instead of the start key SK, the resistance element R is excluded from the series circuit of relay 10 and relay 16. Under this circumstance,

relay 16 operates and prepares a locking circuit for itself through its upper winding at armature 18 and its make contact, the locking circuit being completed upon the engagement with its alternate contact by armature 28 upon the energization of relay 26 after its circuit has been completed by relay 10.

As before, the selector E responds to the impulses of the series to position its wiper 31 in engagement with the contact of its bank corresponding to the number of the matrix. Since relay 16 is locked in its energized position, armature 17 is held in engagement with its grounded make contact. Therefore, when relay 10 deenergizes upon the release of key IWK, ground is connected to wiper 31 in place of battery through the release magnet. The connection of this ground to wiper 31 short circuits the windings of relays similar to relay 34, which relays then deenergize and open the circuit of their associated lamps and also their own locking circuits, thereby wiping out the numerals corresponding to the damaged matrix from the several register panels.

After the last matrix has passed through the inspection and been received in the pressroom and before the matrices for another edition commence to pass the inspection, it will be necessary to wipe out all of the registrations on the register panel. To do this, each sending station has been provided with a complete-wipe-out key CWK, the operation of anyone of which completes the circuit for relay 33. Relay 33 operates and attracts its armature, thereby removing battery from the common locking conductor 44. All of the relays, such as relay 34, which are locked up to the common locking conductor 44 deenergize when the battery is removed therefrom. As each relay deenergizes, it opens the circuit of the signal lamp associated therewith to wipe out the registration on the panel.

Should the selector E get out of operating order, the operator at transmitting station No. 1 may use the selector E' by operating the change-over key COK. Before operating this key, the operator will look at lamp 41 at his station to see if the selector E' is in use. If selector E' is in use, lamp 41 will be lighted, having been lighted in a manner similar to that in which lamp 41' at station No. 2 was lighted. The operation of change-over key COK completes parallel circuits for lamps 42 and 42', and relays 5 and 5'. Lamp 42 at station No. 1 lights to indicate to the operator that his change-over key COK is in the operated position. Lamp 42' at station No. 2 indicates to the operator of that station that his selector E' is being used by the operator at station No. 1. Relay 5 operates when its circuit is completed and attracts its armatures 6 and 7 into engage-

ment with their alternate contacts, thereby connecting the impulse device S and start key SK at station No. 1 with relays 8 and 10 of the selector E'. The operator at station No. 1 now proceeds as in the operation of selector E to operate selector E'. The release of change-over key COK extinguishes the lights 42 and 42' and disconnects station No. 1 from selector E'.

The operation of relay 5', following the operation of change-over key COK at station No. 1, disconnects the impulse device S' at station No. 2 from selector E' so that the operator at station No. 2 can in no way mutilate the operation of the selector E' by station No. 1.

The operation of change-over key COK' at station No. 2 lights the signal lamps 42 and 42' for the purpose already explained, operates relay 5' to disconnect the impulse device at station No. 2 from selector E' and connect it to selector E, and operates relay 5 to disconnect impulse device S of station No. 1 from the selector E to prevent mutilation of signals from transmitting station No. 2.

It will now be appreciated that, by providing two groups of lamps, one group of ten lamps and one group of one hundred lamps, and a two-motion selector switch having access to the ten lamps through a vertical wiper and having access to the one hundred lamps through a rotary wiper, a plurality of signals of the order of three digits can be registered by the transmission of signals corresponding to two digits when all of the signals are of the same order of three digits. More explicitly, after the "thousands" digit has been registered, as many as one hundred signals of that "thousands" order can be registered without the necessity of registering the "thousands" digit for each of the hundred signals. In the instant embodiment, the "thousands" digits are used to display the edition nomenclature. This display in a different embodiment could be in the form of numerals, or other characters, merely by changing the register panel.

Although I have described the system of my invention in its preferred application, it is not my intention to be limited to the exact foregoing disclosure since there are undoubtedly modifications and adaptions which can be made by those skilled in the art without departing from the spirit and scope of the invention.

Having thus described my invention, what I consider new and what I desire to have protected by Letters Patent will be pointed out in the claims which follow.

What is claimed is:

1. In a signaling system, signaling devices, a selector switch, a transmitter for transmitting impulses, means for operating said switch in response to impulses trans-

- mitted by said transmitter to select one of said devices, the number of impulses for operating the switch to select the device being the same for operating and return to normal of the device, means cooperating with said switch operated at will to initiate the release of said switch and normally conditioned to operate the selected device simultaneously with said initiation, and means cooperating with said switch also operated at will either before or after the selection of a device to condition said second-mentioned means to restore the selected device simultaneously with the initiation of the release of said switch.
2. In a signaling system, a selector switch, a plurality of signaling devices, each device adapted to be operated by an impulse of current of negative polarity and restored by a current impulse of positive polarity, a transmitter for transmitting impulses, means for operating said switch in response to impulses transmitted by said transmitter to select one of said devices, the number of impulses for operating the switch to select the device being the same for operating and return to normal of the device, means for releasing said switch after such selection, means cooperating with said switch operable at will to initiate the operation of said release means and simultaneously therewith transmit either a positive or negative impulse to the selected signaling device, and means cooperating with said switch controlled at will to determine the polarity of the impulse transmitted.
- 30 In witness whereof, I hereunto subscribe my name this 5th day of November, A. D 1929.
